UNITED STATES PATENT OFFICE.

RICHARD E. HESS, OF MILWAUKEE, WISCONSIN.

LAMP-BRACKET.

1,164,283.

Specification of Letters Patent. Patented Dec. 14, 1915.

Application filed March 3, 1913. Serial No. 751,740.

To all whom it may concern:

Be it known that I, RICHARD E. HESS, a citizen of the United States, and resident of Milwaukee, in the county of Milwaukee and State of Wisconsin, have invented new and useful Improvements in Lamp-Brackets, of which the following is a description, reference being had to the accompanying drawings, which are a part of this specification.

10 This invention relates to improvements in lamp brackets and has for its object to provide a simple and durable support for electric or other lamps, capable of a variety and great range of adjustments.

15 A further object of the invention is to provide a lamp bracket in which when used with electric lamps, the circuit wires are protected from injury by the portions of the brackets.

20 A further object of the invention is to provide a lamp bracket of simple construction, strong and durable and which may be manufactured for a minimum cost.

25 With the above and other objects in view, the invention consists of the improved lamp bracket and its parts and combinations as set forth in the claims, and all equivalents thereof.

30 In the accompanying drawing in which the same reference characters indicate the same parts in all of the views: Figure 1 is a vertical sectional view of the improved lamp bracket shown in connection with the circuit wires and a portion of an incandescent lamp socket; and Fig. 2 is a view taken at right angles to Fig. 1.

35 Referring to the drawing the numeral 5 indicates the flanged tubular base member of the improved lamp bracket having the upper portion of its bore 6 of conical formation with the larger diameter extending uppermost to receive the tapered pin 7 of the pivot block 8 mounted on top of the base member. The lower portion 9 of the base bore is of 40 larger diameter than the upper portion to provide the shoulder 10 against which a coiled spring 11 surrounding the lower extension 12 of the pin bears. A nut 13 threaded on the extension and bearing 45 against a washer 14 interposed between the nut and the spring serves, in connection with the spring, to yieldingly and frictionally hold the pivot block in adjusted position on the base.

50 Two spaced parallel bars 15 positioned on opposite sides of the block 8 and pivoted

thereto by the bolt 16 form the lower vertical member of the bracket. Portions of the bars above the block are held in spaced relation by the spools 17 and 17' positioned 60 between the bars and held by the bolts 18 and 18' which extend through the bars and the spools. The spools may be formed of insulating material if desired to better protect the circuit wires 19 positioned between the 65 bars and engaging the spools.

The upper or approximately horizontal member 20 of the bracket is also formed of two parallel bars 21 which are pivoted to the upper end of the vertical member by the bolt 70 18', are positioned against the outer faces of the upper spool 17' and are interposed between the said spool and the bars 15; the spool serving to space the bars 21 apart.

A U-shaped lamp holding member 22 pivoted to the free end of the upper member 20 by a bolt 23 is provided with a threaded opening 24 through its lower portion 25 to receive the upper end of the threaded lamp socket member 26.

80 The upper ends of the lamp holding member 22 are spaced apart by a spool 27 which is mounted on the bolt 23, the said upper ends being positioned between the spool ends and the bars 21.

85 The insulated circuit wires 19 extend over and around the spools and are held in position between the bars thereby by extending the wires on opposite sides of adjacent spools and at the points of bends by positioning one of the wires on each side of the spools.

90 The frictional engagement of the members at the joints may be increased or diminished by means of the nuts 27' threaded on the 95 bolts 18, 18' and 23.

Screws 28 serve to fasten the base to any desirable support.

95 In use the frictional engagement of the members at the joints serves to hold the 100 members in adjusted position and the yielding connection of the vertical member permits the upper portion of the bracket to be swung horizontally to any position desired and to be held in its adjusted position.

105 From the foregoing description it will be seen that the lamp bracket is of very simple construction and well adapted for the purpose described.

110 What I claim as my invention is:

1. A lamp bracket, comprising a base member, a block pivotally connected there-

to, a pair of spaced parallel bars pivoted to the block, another pair of spaced parallel bars pivotally connected to the outer ends of the first mentioned bars, spacing members 5 interposed between said bars, and a U-shaped lamp holding member having its stem portions pivoted to the outer ends of the second mentioned bars, the space between said bars serving to receive electric 10 circuit wires.

2. A lamp bracket, comprising a base member, a block yieldingly pivotally connected thereto, a pair of spaced parallel bars pivoted to the block, another pair of spaced 15 parallel bars pivotally connected to the outer ends of the first mentioned bars, spacing members interposed between said bars, and a U-shaped lamp holding member having its stem portions pivoted to the outer 20 ends of the second mentioned bars, the space between said bars serving to receive electric circuit wires.

3. A lamp bracket, comprising a base member having a vertically extending opening, a block mounted on the base member and having a pin which extends through the opening of the block, a spring engaging the base member and the pin for holding the block yieldingly pivotally in engagement with the base member, a pair of bars pivotally connected to the blocks and extending in parallel alinement, spools spacing the bars apart, means extending through the bars and the spools for holding the parts 30 together, a second pair of bars pivotally connected to the free ends of the first mentioned bars, spools spacing the second mentioned bars apart, and a lamp holding member 35

ber pivotally connected to the outer ends of the second mentioned bars, the spacing 40 between said bars serving to receive electric circuit wires which are held in position by the spools.

4. A lamp bracket, comprising a base member having a vertically extending tapered opening, a block mounted on the base member and having a tapered pin which extends through the tapered opening of the base, a coiled spring surrounding the pin and bearing against the base member, a 50 means carried by the pin for engaging the spring, a pair of parallel bars engaging opposite sides of the block and pivotally connected thereto, said pivotal connection being at right angles with relation to the pivotal 55 connection of the block and the base, spools spacing the bars apart, bolts extending through the bars and the spools for holding the parts together, a second pair of bars pivotally connected to the free ends of the 60 first mentioned pair, spools spacing the second mentioned bars apart, and a U-shaped lamp holding member having its stem portions pivotally connected to the outer free 65 ends of the second mentioned bars, said U-shaped member provided with a threaded opening for receiving a lamp socket, the spacing between said bars serving to receive electric circuit wires which are held in position by the spools.

In testimony whereof, I affix my signature, in presence of two witnesses.

RICHARD E. HESS.
